Joseph E. Poole,

INVENTOR

Victor J. Evans

ATTORNEY

MIURA'S

WITNESS: _____

UNITED STATES PATENT OFFICE.

JOSEPH EDWARD POOLE, OF PRETORIA, SOUTH AFRICA.

CLOTHES HOLDER.

Application filed April 21, 1928. Serial No. 271,935.

My present invention has reference to a simple, cheap and effective means for clamping various articles of clothes upon a clothes line, and my primary object is the provision 5 of a means for this purpose that is designed to remain permanently on the clothes line, movable longitudinally on said line and having at its opposite ends means for gripping washed clothes thereon, the said gripping 10 means being readily releasable to permit of the removal of the clothes therefrom when the latter are dried.

To the attainment of the foregoing, the invention consists in the improvement as hereinafter described and definitely claimed.

In the drawings:

Figure 1 is a side elevation of my improvement in applied position.

Figure 2 is a top plan view thereof.

Figure 3 is a sectional view approximately on the line 3—3 of Figure 2.

Figure 4 is a sectional view on the line 4—4 of Figure 1.

Figure 5 is a perspective view of one of the 25 clothes engaging elements or clamps of the improvement.

Figure 6 is a similar view of the body of the improvement.

Figure 7 is a similar view of the spring 30 employed.

Referring now to the drawings in detail, the numeral 1 designates a clothes line and 2 articles of clothing which have been washed and which are designed to be clamped upon 35 the line for the drying thereof.

My improvement may, of course, be constructed of any desired material, and essentially includes a body member in the nature of a block 3. The block on its upper edge is formed with a longitudinal groove 4 that receives the bottom portion of the clothes line 1 therein. Secured on the block, preferably through the medium of a staple 40 there is a yoke 5. The yoke 5 has its top extended at a suitable distance above the grooved edge of the block 3, and the top of the said yoke, at its corners may be notched. The yoke is designed to have received therein one of the beveled upper corners 6 of the 45 clamping blocks 7. Each of the clamping blocks has its flat under face formed with a longitudinal groove 8 to register with the groove 4 in the block 3 and to permit of the

said clamping blocks being swung at outward angles with respect to the yoke and with 55 respect to the block.

Below its connection with the yoke, the block 3 has a transverse round opening 9 therethrough, and received in this opening there is a coiled central portion 10 of a spring. 60 The opposite end convolutions of the spring are formed with rounded arms 11 that merge into hook-like ends 12. For distinction the outer elements of the ends 12 are indicated by the numerals 13. The hooks are designed 65 to be received in transverse grooves 14 in the clamping blocks 7, the arms 12 and 13 of the said springs being disposed in contacting engagement with the opposite faces of the clamping blocks.

The improvement is comparatively long, so that the washed clothes 2 may have their ends received between the clamping blocks 7 and arranged on the clothes line for a greater length than is ordinary with devices 75 of this type. The improvement is designed to remain a permanent fixture on the clothes line, which latter, of course, is suitably supported. Of course, any number of clamps or clothes holders in accordance with my improvement may be arranged on the line. To remove the clothes it is merely necessary to cant the outer ends of the clamping blocks 7 in an upward direction.

While I have illustrated a satisfactory embodiment of my improved device, my features of invention are capable of extended application, and I do not wish to be limited to the specific structure herein shown and described.

Having described the invention, I claim:

1. In a device for clamping clothes on a clothes line, a body block having its upper edge grooved to receive a clothes line therein, a yoke centrally fixed to the sides of the block and extending thereabove, clamping blocks having their upper corners beveled and their lower flat faces grooved and one of the ends of each of the clamping blocks designed to be received in the yoke, and spring means carried by the body block and exerting a tension upon the clamps for urging the same toward the body block.

2. In a device for clamping clothes on a clothes line, a body block having its upper edge grooved to receive a clothes line therein, 100 a yoke centrally fixed to the sides of the

block and extending thereabove, clamping blocks having their upper corners beveled and their lower flat faces grooved and one of the ends of each of the clamping blocks designed to be received in the yoke, and spring means carried by the body block and exerting a tension upon the clamps for urging the same toward the body block, said body block having a central opening therethrough, a

spring having a central coiled portion received through the opening and having its ends formed with arm extensions which merge into hooks, and each of the clamps having a groove to receive the central portion of the hook therein. ¹⁰ ¹⁵

In testimony whereof I affix my signature.

JOSEPH E. POOLE.
